(57) **CLAIM**

The ornamental design for a tool box as shown and described.

DESCRIPTION

FIG. 1 is a top, front, and right perspective view of a tool box showing my new design;
FIG. 2 is a front elevational view thereof;
FIG. 3 is a rear elevational view thereof;
FIG. 4 is a left side view thereof;
FIG. 5 is a right side view thereof;
FIG. 6 is a top plan view thereof;
FIG. 7 is a bottom plan view thereof; and,
FIG. 8 is a bottom, front, and left perspective view thereof. The broken lines in the drawings illustrate portions of the tool box which form no part of the claimed design.
